UNITED STATES PATENT OFFICE.

CHARLES G. ADSIT, OF ATLANTA, GEORGIA.

DISTILLING APPARATUS.

1,386,484.

Specification of Letters Patent.

Patented Aug. 2, 1921.

Application filed September 14, 1920. Serial No. 410,289.

To all whom it may concern:

Be it known that I, CHARLES G. ADSIT, a citizen of the United States of America, residing at Atlanta, in the county of Fulton and State of Georgia, have invented certain new and useful Improvements in Distilling Apparatus, of which the following is a specification.

My present invention relates to distilling apparatus, and particularly to apparatus for cracking and distilling crude petroleum or other oils or liquids in a continuous process. Among the objects of my invention may be especially mentioned—

- 15 1. The provision of electric means for heating the distilling tube or retort;
2. The construction of the retort proper to constitute the secondary of an electric winding, so that current introduced therein generates the heat required for the distilling process;
- 25 3. The provision of means for supplying a continuous flow of liquid to the retort and overflow discharge therefrom associated with the vapor chamber, from which the distilled vapors are withdrawn or permitted to escape;
4. Means for maintaining the vapor chamber under pressure;
- 30 5. The provision of a series of retorts, or retort batteries, at different temperatures, the overflow from one being connected to the intake of the next in series;
- 35 6. Means for maintaining the inner surface of the retorts free from deposits or other accumulations thereon;
7. Means for withdrawing sediment from the bottom of the retort;
- 40 8. Regulating and control devices for maintaining the chamber of each retort, or retort battery, at desired temperature, and for insuring the desired flow of liquid through the apparatus;
- 45 9. Indicating means for disclosing the temperature and pressure conditions in the retort;

10. Various features of construction and operation hereinafter described or indicated in the accompanying drawings, in which, 50 Figure 1 is a schematic vertical section through a distilling apparatus in which my invention is embodied in one form;

Fig. 2 is a similar view of a modified construction;

55 Fig. 3 is a similar view of a further modification;

Fig. 4 is a similar view of another modification; and

Fig. 5 is a side elevation of the latter.

In the form shown in Fig. 1, the oil or other liquid to be distilled or cracked, is supplied to the apparatus from any suitable source, such as the tank diagrammatically illustrated at A, through a pipe B; and a force pump C. The liquid, which for brevity I will hereinafter refer to as "oil," flows through the pipe B to the lower portion of the chamber D of the retort E formed from an iron or steel tube. The lower end of the latter is closed by a cap F, while its upper end opens to the distillate dome G. Wires H, from any suitable source of current supply, preferably alternating current, lead to the retort and are coiled around the same, but insulated therefrom in any suitable manner, as by an insulated casing I on the retort. A switch S is provided to control the circuit. A jacket I' surrounding the coil prevents radiation and consequent loss of heat from the retort. As will be noted, 60 the retort tube or pipe E is carried up into the dome G a sufficient distance to form a sump J, which receives the overflow from the top of the retort. A scraper K, (Fig. 2) may be arranged within the retort to 65 keep its walls free from accumulations or deposits thereon. This scraper is journaled in a spider K' at the top of the retort, and passes out through a stuffing box K² at the bottom to any suitable driving means (not 70 shown). At the top of the dome G is an escape pipe L for the distilled vapors, the pipe having arranged therein a spring 75 pressed valve which may be regulated to maintain the pressure in the dome as high 75 as desired. A discharge pipe M opens from the bottom of the sump J and drains the undistilled overflow liquid therefrom through control valve O. A pyrometer P with exposed dial is arranged in the upper portion 80 of the retort to indicate the temperature of the oil at that point. A pressure gage R opens to the top of the dome G, and its indication governs the adjustment of the escape valve N for the distilled vapors. A 85 liquid gage V discloses the level of the overflow in the sump J. At the bottom of the retort a clean-out pipe Y, provided with a suitable control valve opens through the cap F, so that any sediment in the retort 90 may be discharged at will.

The operation of the apparatus is as fol-

lows: Cold oil is pumped from the source A into the retort E below the portion of the latter surrounded by the coil and heating jacket I', and slowly passed up through the 5 zone surrounded by the heating jacket. If the switch S is closed, the flow of alternating current through the wire H (preferably copper) coiled around the retort, induces in the latter a secondary current proportional 10 to the ampere turns in the coil. Thus, current of high density is caused to circulate within the iron or steel pipe forming the retort and heats the latter through its inherent electrical resistance. Any temperature 15 desired within the limits of operation of the distilling process may be obtained in the retort. Due to the even distribution of the current flow in the wall of the retort, and to the fact that no flame or fire is employed, there is no danger of producing in 20 the retort the "hot spots" commonly incidental to flame or fire heated retorts. Even should the internal structure of the metal tube be non-uniform, so that one portion 25 thereof presents more or less resistance than another to the flow of current, and therefore tends to become hotter, or vice versa, the tendency to local over-heating is automatically compensated. The electric 30 resistance in the hotter portion will rise and automatically pass less current, thereby removing to some extent the excess heat at that point. The flow of the current in the primary coil may be controlled by electrical 35 devices of any suitable sort, such as induction regulators or separately controlled electric generators, or by rheostats, so that any desired temperature within the still may be obtained and this temperature held practically constant within very close limits 40 throughout the distillation process.

As the cold oil flowing upward through the retort does not come in contact with the heated portion of the oil under distillation, 45 or the distilled vapor, there is no retardation of the process caused by the continuous feed of the cold oil, and none of the vapor rising from the top of the retort is condensed.

While it is possible to permit the distilled 50 vapor to pass off at atmospheric pressure, or below, (*i. e.* under vacuum,) I prefer to maintain the dome under pressure. By use of the regulating valve N not only is pressure maintained within the dome, but it is 55 kept practically constant during the distillation process, regardless of the flow through the valve. A spring pressed valve of this type also serves as a safety, since it automatically relieves excess pressure. The 60 distilled vapors or gases after leaving the dome through the pipe L, are carried to a condensing apparatus of any sort, (not shown) while the overflow from the top of the retort may be delivered to a collection

65 tank, or as indicated in Fig. 3, it may be led to a second still arranged in series with the first, but having the coil or current so differentiated from that of the first still as to induce in the wall of the second retort a current of greater density, and thus to raise the 70 temperature of the retort above that of the preceding retort in the series. With the same current a like result may be obtained by varying the material of the second retort so as to offer a greater resistance to the flow 75 of the current, or, alternatively, the diameter of the second still may be diminished to afford a smaller volume of oil passing therethrough, or the speed of the feed may be varied in a still of the same diameter; so as 80 to insure a higher temperature in successive stills of the series. In this way distillates of different boiling points are successively removed from the crude oil. It will be noted that in spite of the relatively rapid feed to 85 the apparatus, the effect of slow distillation is secured since the oil passes from the relatively cool bottom of the retort slowly upward through the heated zone and reaches the desired distillation temperature gradually. This is a very valuable feature in 90 distillation processes, especially for cracking oils.

Tar or fixed carbonaceous products of the 95 distillation process follow the flow of oil through the still and are carried out through the pipe M with the residue. Sand or any other substance too heavy to be carried in suspension so that it sinks to the lower portion of the still, may be cleaned out periodically through the pipe Y. The scraper K, comprising a steel blade or brush in the form of a spiral with long pitch, serves the double purpose of cleaning the inner face of the 100 retort, and of agitating the oil in the latter 105 so that the interior and exterior temperatures of the oil are maintained as uniform as possible at all points.

In the stills shown in Figs. 1 to 3 inclusive, I have arranged the retort vertically. In 110 Figs. 4 and 5, I have shown the retort inclined. Moreover, I have shown a battery of retorts arranged in parallel and taking their feed from a bottom drum X and delivering to a top dome G common to the battery. From the dome G the residue passes by pipes M to a collection chamber or second battery, as in Fig. 3. In this construction I have shown the feed drum X provided at X' 115 with a series of ports axially aligned with the retort tubes E to permit the introduction of a cleaning tool therethrough upon the removal of the cover plates X². It would of course be possible to provide scrapers, as in the construction shown in Fig. 2, if this were 120 preferred.

Another feature of construction which may be pointed out is the fact that each re-

tort tube E constitutes a self-contained element which may be inserted, or removed from position by disconnection at its end flanges E² from the corresponding flanges

5 of the port holes opening to the upper and lower drums G and X.

Another feature common to all of the types of construction illustrated, and of particular value in the process, resides in the 10 fact that the distilled vapors or gases which collect in the dome above do not come in contact with the heated retort tubes. Destructive distillation is thus prevented.

I claim—

15 1. Distillation apparatus comprising a metallic retort, a primary coil surrounding the same but insulated therefrom, means for supplying liquid to the retort, and means for recovering the vapors distilled there-

20 from upon the heating of the retort by induced current following the flow of alternating current through the primary coil.

25 2. Distillation apparatus comprising a metallic retort, a primary coil surrounding the same but insulated therefrom, means for flowing liquid through the retort, and means for recovering the vapors distilled therefrom upon the heating of the retort by induced current following the flow of alternating current through the primary coil.

30 3. Distillation apparatus comprising a metallic retort, a primary coil surrounding the same but insulated therefrom, a distillate chamber communicating with the upper

35 portion of the retort, means for flowing liquid upward through the retort, means for leading off the undistilled liquid passing through the retort, means for leading off from the said chamber the distillate resulting from the heating of the retort following the flow of alternating current through the primary heating coil.

40 4. Distillation apparatus comprising a metallic retort, a primary coil surrounding the same but insulated therefrom, a distillate chamber communicating with the upper

45 portion of the retort, means for flowing liquid upward through the retort, means for leading off the undistilled liquid passing through the retort, means for leading off from the said chamber the distillate resulting from the heating of the retort following the flow of alternating current through the primary heating coil, together with means for

50 maintaining the distillate chamber under pressure.

55 5. A distillation apparatus comprising a tubular metallic retort, a primary coil surrounding but insulated therefrom, means for introducing liquid to the lower portion of

60 the retort, means for collecting the distillate at the upper portion of the retort, and means for connecting the primary coil to a source of alternating current whereby, upon

the flow of current through the primary, the 65 tubular retort is heated by the current induced therein.

6. In combination with an apparatus such as specified in claim 5, a source of liquid supply, piping connecting the same to the lower 70 portion of the retort, and means for feeding the liquid continuously from the source of supply to the retort so as to permit the distillation to be carried on as a continuous process.

7. An apparatus such as specified in claim 5, having an outlet at the bottom of the retort for the discharge at will therefrom of sediment accumulating in the retort.

8. In a construction such as specified in 80 claim 5, means for maintaining the collecting chamber of the retort under predetermined pressure.

9. In an apparatus such as specified in claim 5, means for regulating the current 85 supplied to the primary coil to vary the temperature of the retort resulting from the induced current therein.

10. A distillation apparatus comprising a series of retorts of the type specified in 90 claim 5, and means for varying the induced current in the several retorts to graduate the temperatures of the different retorts of the series.

11. In a distillation apparatus, a tubular 95 metallic retort, a primary winding surrounding but insulated therefrom, a collecting chamber at the top of the retort, a discharge for the undistilled liquid passing through the retort, and means for feeding liquid continuously into the lower portion of the retort, together with means for connecting the primary winding to a source of alternating current whereby, upon the flow of current therethrough, the retort is heated by the 105 secondary current induced therein.

12. A distillation apparatus, comprising a series of retorts of the type specified in 110 claim 5, means for controlling the electrical conditions at the several retorts of the series to maintain the same at different temperatures, and means for leading the undistilled liquid from one retort to the retort next in the series.

13. A distillation apparatus, comprising 115 a series of retorts of the type specified in claim 5, means for controlling the electrical conditions at the several retorts of the series to maintain the same at different temperatures, and means for leading the undistilled 120 liquid from one retort to the retort next in the series, the successive retorts in the series being maintained at successively higher temperatures.

14. A continuous distillation apparatus 125 comprising a series of metallic retorts, an over-flow discharge connection between successive retorts in the series, means for col-

- lecting the distillate from each retort, and means for heating the retorts by electric current induced therein, together with means for passing the liquid to be distilled successively through the retorts in the series.
15. A continuous distillation apparatus comprising a series of metallic retorts, an over-flow discharge connection between successive retorts in the series, means for collecting the distillate from each retort, and means for heating the retorts by electric current induced therein, the electric conditions for successive retorts being raised to maintain successively higher temperatures therein.
16. In a continuous distillation apparatus, a metallic retort, means for passing liquid continuously therethrough, means for inducing an electric current therein to heat the same, and means for cleaning the inner face of the retort during the operating of the apparatus.
17. In a continuous distillation apparatus, a metallic retort, means for passing liquid continuously therethrough, means for inducing an electric current therein to heat the same, and means for cleaning the inner face of the retort during the operating of the apparatus.
18. In a continuous distillation apparatus, a feed drum, a collecting drum, and a battery of retorts extending between and connected to said drums in parallel, means for continuously introducing liquid into the feed drum, means for leading off the distillate from the collecting drum, and means for heating the retorts to distilling temperature.
19. In a continuous distillation apparatus, a feed drum, a collecting drum, and a battery of retorts extending between and connected to said drums in parallel, means for continuously introducing liquid into the feed drum, means for leading off the distillate from the collecting drum, and electrical means for heating the retorts to distilling temperature.
20. In a construction such as specified in claim 18, metallic retorts, and means for inducing electric currents therein to heat the same.

In testimony whereof I have signed my name to this specification.

CHARLES G. ADSIT.
